AIR REGISTER

Ernest H. Peabody, New York, N. Y.

Application December 6, 1934, Serial No. 756,247

14 Claims. (Cl. 158—1.5)

This invention relates to air registers and particularly to the type disclosed in the Peabody Patent 1,527,214 of February 24, 1925.

In burners of the type referred to, admission of the air necessary for proper combustion of the fuel is governed by regulation of a series of air doors, which may be simultaneously adjusted for regulating the rotation of the air, and may also be simultaneously adjusted to admit varying amounts of air. This multiplicity of doors may give the entering air a rotary motion for promoting proper mixture with the fuel and for effecting a smooth even discharge from the burner throat.

For most furnaces, it is desirable and even necessary that the burner flame be substantially circular in outline, so that the heat will be projected evenly in all directions. The air register of the patent referred to is intended to accomplish this result.

In other furnaces of special design, the operation would be improved if the flame were other than strictly symmetrical.

The objects of the present invention are to provide an air register which will be adaptable to meet such special requirements and which will have simple, practical and effective means for "distorting" or displacing the flame at will, to meet special furnace requirements, such as to reach particular portions of the furnace which would not be reached by an ordinary symmetrical flame. Also to accomplish this without destroying the air rotation imparted by the main air doors. It may be desired to distort the air flow for other purposes in cases where the register is not used in combination with a fuel admission system.

It is also an object to provide means to control the form of the flame which may be used, if so desired, to render a flame symmetrical which otherwise, due to other causes, would be unsymmetrical.

Other objects of the invention are hereafter set forth or may be apparent from the accompanying specification, claims and drawings.

The drawings show by way of illustration certain preferred embodiments of the invention and what are considered now the best modes of applying the underlying principles. Other embodiments of the invention employing the same or equivalent principles may be used and structural changes made as desired by those skilled in the art without departure from the present invention and within the spirit of the patent claims.

Fig. 1 in the drawings is a broken front elevation and partly sectional view illustrating the invention as incorporated in an air register of the conical type.

Fig. 2 is a broken vertical sectional view of the same as on substantially the plane of line 2—2 of Fig. 1.

Fig. 3 is a broken sectional detail illustrating the invention as applied to an air register of the cylindrical type, this view being taken as on substantially the plane of line 3—3 of Fig. 4.

Fig. 4 is a broken side elevation and part sectional view of the parts appearing in Fig. 3.

Fig. 5 is an enlarged broken sectional view as on line 5—5 of Fig. 1.

Fig. 6 is a similar view as on line 6—6 of Fig. 1.

In Figs. 1 and 2, the front and back plates of a conical type register are indicated at 5, 6, connected in spaced relation by inclined bolts 7, providing the hinge pins for the air doors 8. These parts may be constructed and arranged as in the patent referred to with spacer sleeves 9, surrounding the bolts and hinge lugs 10, at the ends of the doors, pivoting on the sleeves, details of the same appearing in Figs. 5 and 6.

The air doors are indicated as of sufficient extent to overlap in the closed position and are further indicated as simultaneously operable, as in the patent, by means of pins 11, on an adjusting ring 12, operating in slotted inwardly extending lugs 13, at the outer ends of the gates. The adjusting ring is shown as formed with gear teeth 14, engaged by pinion 15, which can be turned by a hand crank 16, on the outer end of the shaft 17, carrying the pinion.

By turning the hand crank 16, it will be seen that the air doors, which may be either flat, or curved, as shown, may be simultaneously turned on their pivotal supports to admit more or less air through the register and that these doors will impart the desired rotary motion to the entering air.

For securing the air doors in the desired positions of adjustment, a lock nut 18 is provided on the pinion shaft which can be set up tight against a boss 19 on the front plate. Other methods such as a self locking worm and wheel arrangement may be employed.

For varying the air admission to suit particular requirements, auxiliary air doors are provided, which may be individually adjusted to regulate the air admitted by the main air doors.

These auxiliary air doors are designated 20 and they are shown as pivoted on the same centers as the main air doors and as of a width to par-

tially or entirely close the spaces between adjoining main air doors.

The pivotal mounting of the auxiliary doors is effected in the illustration by providing the hinge sleeves 21, at the inner edges of the same of a length less than the distance between the hinge lugs 10 of the main doors and engaged on the spacer sleeves 9, between the hinge lugs 10. These auxiliary doors may be made of sheet metal, 10 in which event, the hinge sleeves may be formed by simply curling or rolling the inner edges of the same.

Individual adjustment of the auxiliary air doors is effected in the construction shown by rods 22, 15 having cranked ends 23, engaging in slots 39 in flanges 24, at the outer ends of such doors. These adjusting rods are shown as having screw mounting at 25, in the front plate and as held in 20 individually adjusted relation by lock nuts 26, on the screw portions of said adjusting rods. The adjusting rods are susceptible to control at a point removed from the burner.

The auxiliary air doors 20, by the construction disclosed may be individually adjusted and secured 25 entirely independently of the main air doors. Thus the main air doors may be opened more or less to change the volume of air admitted without varying the special settings of different auxiliary doors. If with a change in the main air doors 30 the auxiliary air doors require different setting, this can be readily effected without disturbing the main door setting. Fig. 1 illustrates how one or any number of the auxiliary air doors may be entirely or partly closed, while the main doors may 35 be fully opened, partly or fully closed. Hence the burner flame may be deliberately distorted and inclined at will toward different portions of a furnace or if already distorted by some cause may be restored to a symmetrical form.

40 Fig. 5 illustrates how, when an operating platform plate is placed over the front of the burner as at 27, the means for adjusting and securing the main and auxiliary air doors may be brought out through the front of this plate by tubing 28, 45 29, of square cross section engaged over the squared ends 30, 31, of the pinion shaft 17 and cranked rods 22, and surrounding larger size square tubing 32, 33, engaged over the lock nuts 18, 26, respectively. In such case, the hand crank 16 for setting the main doors is fixed on the other end of tubing 28, instead of being directly attached to the pinion shaft 17. The outer ends of tubing 29, for turning the auxiliary door setting cranks 50 may be equipped with suitable heads as indicated at 34, to enable them being readily turned by a hand wrench or the like, and the lock nut securing tubes 32 and 33, may be equipped with suitable wrench heads as indicated at 35, 36. By these 55 operating extensions of square tubing, the main and auxiliary air doors may be readily adjusted and secured to meet any normal or unusual conditions.

Figs. 3 and 4 show how the invention may be applied to an air register of the cylindrical type, 60 where the bolts 7, and the doors supported thereby are parallel, forming portions of a cylinder instead of inclined and forming portions of the frustum of a cone as in the first example considered. Except for this difference in disposition, the parts 65 are substantially the same and corresponding reference characters have therefore been used. In constructions such as shown, the auxiliary air doors may each have a bend in them as indicated at 37, so that in fully closed position they will 70 be clear of the arcs 38, representing the travel of

the main doors and hence never interfere with the opening and closing movements of the main air doors. The slotted flanges 24, Figures 1 and 3, serve as reinforcements bracing the "bent" or angularly related portions of the auxiliary air 5 doors, which is an advantage when such doors are made of sheet metal.

To limit the travel of the auxiliary air doors so that they may not block adjustment of the main air doors, the adjusting cranks 23 and cam 10 slots 39 may be proportioned and arranged, as indicated particularly in Fig. 3, so that such cranks in coming to the inner ends of such slots in both extremes of movement will serve as stops limiting both opening and closing movements of the 15 auxiliary doors.

Operation

By adjustment of the single control represented by the hand crank 16, Figs. 1 and 6, the main air 20 doors 8, may all be simultaneously shifted to vary the total volume of air admitted by the register. Then by adjustment of selected auxiliary air doors 20, through the medium of the crank and cam slot connections 23, 24, the amount of air 25 actually admitted at any point around the circumference of the register may be modified and controlled and hence more or less air be fed to different sides of the flame. Control of the flame can thus be effected at will. If in trimming down 30 the air at one side the total volume is reduced too much, then the main air doors may be opened more and this without disturbing the setting which may have been given certain or all of the auxiliary air doors. In corresponding fashion, if 35 a setting of the main air doors disturbs the effect of the auxiliary air doors, then the latter may be adjusted without touching the adjustment of the main air doors. The adjusting cranks 23, by limiting the extent of swing of the auxiliary air 40 doors, serve as convenient stops, preventing these auxiliary doors from obstructing or interfering with adjustment of the main air doors. The auxiliary doors being mounted on the same centers as the main air doors and lying close to the backs 45 of the main doors in the fully open relation, offer no material obstruction to the inflow of air. Also, as will be clear, the addition of the auxiliary air doors does not limit or change the usefulness of the air register for either natural draft or for 50 forced draft as when used with a wind box as indicated at 39, in Fig. 2. When air registers are installed in a wind box, there may be an unequal distribution of air in the box, depending upon the point and method of admitting the air to the 55 box. Under these conditions, the auxiliary doors may be used effectively for securing a proper flow of air into the registers. The construction also is of such a character, that if found desirable or necessary, one or any number of the auxiliary air doors may be omitted and for some installations, the register be made up with only a limited number of the auxiliary air doors, as for example, one auxiliary air door associated with every alternate 60 main air door.

The parts are of simple substantial construction, well adapted to the accomplishment of the objects set forth and such parts furthermore are readily applicable to existing structures.

The square tubing 28, 32 and 29, 33, for operating and securing the main and auxiliary air doors can be quickly applied or removed, as will be clear from Figs. 5 and 6. While tubing of full length square cross-section is illustrated, it will be apparent that circular or other cross-sectional 75

shape tubing may be employed with the inner ends of the same squared or otherwise properly shaped to fit over the head portions 30, 18 and 31, 26 of the door shifting and securing devices.

5 The auxiliary air doors may be designed so as to be capable of either wholly or only partially closing the air passages controlled by the main air doors.

Other modifications and changes are possible 10 all within the true spirit and broad scope of the claims.

What is claimed is:

1. An air register for burners, comprising main and auxiliary air doors pivotally mounted on the same centers, means for simultaneously adjusting 15 all of the air doors of the one kind and means for individually adjusting the air doors of the other kind.

2. An air register for burners, comprising main and auxiliary air doors pivotally mounted on the same centers, means for rocking the main air doors on said centers and means for independently 20 rocking the auxiliary air doors on said same centers.

3. An air register for burners, comprising pivotally mounted main air doors standing in overlapping relation in the closed position of the same, auxiliary air doors shiftable independently of said main air doors to partially or substantially fully close the spaces between the main air doors in the open position of the latter and means for individually positioning and securing different auxiliary air doors in different positions with respect to said main air doors.

4. An air register for burners, comprising pivot 35 bolts, a series of main air doors mounted on said pivot bolts and controlling passage of air through said air register and auxiliary air doors mounted on said same pivot bolts, adjustable on said pivot bolts independently of the adjustment of the main air doors thereon and cooperable with said main air doors to vary the air flow controlled by said main air doors.

5. An air register for burners, comprising pivot 40 bolts, a series of main air doors mounted on said pivot bolts and auxiliary air doors mounted on said same pivot bolts and foldable thereon in closely overlying relation over the outside of said main air doors.

6. An air register for burners, comprising pivot 45 oted main air doors, pivoted auxiliary air doors for closing the spaces between the main air doors and cranked members having connections with the auxiliary air doors to limit adjustment of the auxiliary air doors to non-interfering positions with respect to adjustment of the main air doors.

7. An air register for burners, comprising pivot 50 oted main air doors, pivoted auxiliary air doors for closing the spaces between the main air doors and cranked members having connections with the auxiliary air doors to limit adjustment of the auxiliary air doors to non-interfering positions with respect to adjustment of the main air doors, said connections including flanges on 55 the auxiliary air doors slotted to receive the cranked connections and positioned to serve as

stops limiting the turning movement of the cranked members.

8. An air register for burners, comprising circumferentially arranged adjustable main air doors and pivoted auxiliary air doors operable in 5 the spaces between the main air doors and having end portions angularly related to the balance of the same to provide clearance for free operation of the main air doors.

9. An air register, comprising main and auxiliary air doors, concentrically disposed control means for setting and securing the main air doors, said means having angular head portions, concentrically arranged control means for setting and securing the auxiliary air doors having angular head portions, and operating extensions including concentrically disposed tubing having angular inner end portions fitting the angular head portions of the main air door control means and concentrically arranged tubing having 20 inner angular end portions fitting the angular head portions of the auxiliary air door control means.

10. An air register for a burner, comprising a register casing of substantially circular cross- 25 section having air passages about the periphery of the same, an annular series of curved main air doors adjustable to vary the air admitted through said passages about the periphery of said register casing and auxiliary air doors positioned to control said same air passages but independently of each other and independently of said main air doors to modify the flow of air controlled by said main air doors.

11. An air register for a burner, comprising a 30 register casing having air passages about the peripheral portion of the same, an annular series of curved main air doors adjustable to control flow of air through said passages, auxiliary air doors positioned to control said same air passages 35 and adjustable for modifying the flow of air controlled by said main air doors, means for adjustably setting said main air doors and means for variously setting said auxiliary air doors independently of said main air doors.

12. An air register for a burner, comprising a register casing, a circumferential series of main air doors on said register casing, means for simultaneously adjusting said main air doors, a circumferential series of auxiliary air doors shift- 50 able over said main air doors to control the air passages governed by said main air doors and means for individually setting and securing said auxiliary air doors independently of the adjustment of said main air doors.

13. An air register for a burner, comprising a register casing, a series of main air doors pivotally mounted on said register casing and a series of flow modifying auxiliary air doors pivotally mounted for adjustment on the same centers as 55 said main air doors.

14. An air register for burners, comprising a register casing having front and back plates held by spacers in spaced relation, main air doors pivoted on said spacers and auxiliary air doors pivotally mounted on said same spacers.

ERNEST H. PEABODY.
